United States Patent Office.

ISAAC A. CLARK, OF MARION, NEW YORK.

Letters Patent No. 95,083, dated September 21, 1869.

IMPROVEMENT IN GATES.

The Schedule referred to in these Letters Patent and making part of the same

To all whom it may concern:

Be it known that I, ISAAC A. CLARK, of Marion, in the county of Wayne, and State of New York, have invented a certain new and useful Improvement in Gates; and I do hereby declare that the following is a full and exact description thereof, reference being had to the accompanying drawings, making part of this specification, in which—

Figure 1 shows a plan;

Figure 2, an elevation; and

Figure 3, a detail view.

Like letters of reference indicate corresponding parts in all the figures.

This gate is an improvement upon that patented to V. R. W. Horton, May 19, 1868. In that case an arrangement of friction-rollers was connected with the lower rail of the gate, swinging off and on with it, but stationary in place when the gate was sliding back.

The only difficulty experienced was to always keep the rollers in place, so as to swing back in line with the central bearing or stud that sustained it, when the gate received the sliding movement.

My present invention is designed to obviate this difficulty, and consists in combining with the rollers a guide-bar or brace, which is hinged to the post, and swings around with the gate, thereby keeping the said rollers always the same distance from the post.

In the drawings—

A indicates the gate, and B B the posts, the gate being of that kind that slides half-way back and then swings around.

The gate runs upon the ordinary friction-roller *a* at the top, as usual.

It has also midway, or thereabout, a pair of friction-rollers, *b b*, on which rests and runs the lower rail, the connection with said rail being made by a stirrup or loop, *c*.

Thus far the invention is similar to that of Horton's, before referred to.

I combine with these rollers a brace or bar, *d*, either of metal or wood, which hooks, or otherwise connects, at one end with the stirrup *c*, while at the other it is hinged to the post B, as shown.

By this means, it will be seen that the gate may slide back half way over the rollers *b b*, and then swing around in the usual manner.

In swinging, it will be noticed that the rollers will be retained, by the brace or bar *d*, always the same distance from the post, and hence, in closing, it will strike again over its bearing or stud *f*.

I thus avoid the difficulty experienced in the device at first alluded to, as the rollers can in nowise get displaced. This feature I believe to be original with myself.

At the front of the gate, I make one or more of the rails to project beyond the others, as shown at *g*.

I also cut an obtuse-angled notch, *h*, in its upper surface.

In a slot of the post B, I hang a catch, *i*, provided with a right-angled corner, *k*.

In the forward motion of the gate, the end *g* of the rail strikes the catch *i* and throws it up, and when past the corner *k*, strikes into the notch *h*, and retains the gate against back action.

The novelty in this case is the extreme simplicity of the fastening, requiring no iron, and simply requiring the notching of the rail.

What I claim as my invention, and desire to secure by Letters Patent, is—

The combination of the hinged bar or brace *d* with the rollers *b b*, in the manner described, and for the purpose specified.

In witness whereof, I have hereunto signed my name, in the presence of two subscribing witnesses.

ISAAC A. CLARK.
